UNITED STATES PATENT OFFICE.

WILLIAM L. BARBER, OF PROVIDENCE, RHODE ISLAND.

ENVELOPE OPENER.

Application filed August 4, 1921. Serial No. 489,804.

To all whom it may concern:

Be it known that I, WILLIAM L. BARBER, a citizen of the United States, and a resident of Providence, in the county of Providence and State of Rhode Island, have invented 5 a new and useful Improvement in Envelope Openers, of which the following is a specification.

This invention relates to devices for opening envelopes and the like. A principal object of the invention is to provide an envelope opener that is small and compact in size so as to be adapted to be carried on a chain or in a pocket as well as for desk use, 10 with provision whereby the cutting blade is protected by its holder which serves as a guard when the device is not in use for the purpose of safety as well as to retain the keen cutting edge. A further object is to 15 provide a device that is effective and convenient for its intended purpose, while being especially simple and cheap to manufacture. The foregoing and other objects and advantages of the invention will more 20 fully appear from the following detailed description, and the distinctive features of novelty will be pointed out in the appended claims.

Referring to the drawings:

30 Figure 1 is a side elevation of one embodiment of the invention on an enlarged scale;

Fig. 2 is an end view thereof;

Fig. 3 is a side view showing a slightly 35 different form of the invention;

Fig. 4 is a similar view showing the blade open for use;

Fig. 5 is an end view of the device of Fig. 3; and

40 Fig. 6 is an elevation showing the device in use.

Referring first to Figures 1 and 2, 10 indicates a strip of metal secured to a block 11 which constitutes a hand piece, and may 45 be made of wood or any other suitable material such as rubber, fiber, celluloid, or metal. The metal strip 10 is secured to this finger piece by suitable means, shown as screws 12 at the ends thereof. The metal 50 strip 10, which is in the form of a plate, has a leaf or extension at one side thereof folded over into parallelism, and into proximity to the surface thereof, as indicated at 55 13 to constitute a thin, flat sheath or guard for the edge of the cutting blade when the blade is not in use. It will be understood

that this sheath member 13, instead of being formed by the folding over of an extension of the plate 10 upon itself, may be produced as a separate member suitably secured in spaced relation to the plate 10. 14 indicates 60 the cutting blade which is formed of thin steel, preferably about ten one thousandths of an inch thick which may be hardened and ground, similarly as the blade of a safety razor. This cutting blade is pivoted adjacent one end thereof to the plate 10 as indicated at 15, and it is relatively wide at this end portion as indicated at 14^a, so as to provide a convenient finger piece for opening 65 the blade, tapering thence, as indicated at 14^b, to a relatively narrow outer end which extends inward to the sheath when the blade is closed.

The location of the pivot 15 with reference to the inner corner 14^a of the blade, is such that this corner engages the folded back of the plate 10 when the blade is opened to the proper cutting angle, i. e., about 27°, thus preventing the opening of 70 the blade more than necessary to do its work properly with a shearing action upon the paper. The cutting edge 14^a of the blade is thus fully protected by the sheath when the blade is closed as indicated in Figs. 75 1 and 3, the sides of the blade frictionally engaging the sheath so that the blade will not swing open except when pulled out of the sheath for use by the projecting finger piece portion 14^a. The blade edge is preferably made dull and with a rounding corner at its outer extremity 14^b so that this extremity may act as a leader in inserting the blade in a corner C of an envelope E. The device thus produced is well adapted 80 for desk and like uses.

For adapting the device to be carried on a chain or in the pocket it may be made substantially as already described, but without the hand piece block 11. Such a form is 100 shown in Figs. 3, 4 and 5 where the plate 10' is folded upon itself to provide a sheath 13'. The cutting blade in this case is constructed and mounted in the same way as already described. In this case the holder 105 sheath itself constitutes the holder for the device in use, and the outer end thereof may be provided with a hole 16 for attachment of a chain.

Since the cutting blade is relatively thin, 110 and of the same thickness through its entire length, it is possible to insert it readily in

the flap corner of an envelope and there is nothing to obstruct its passage through the envelope. Inasmuch as the strip 13 is thin, it will be clear that the cutter can press 5 on the envelope while entering under the flap so that it will make a clean cut from one end of the envelope to the other while such envelope is resting on a desk or other flat surface. I am aware that the invention 10 may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I 20 claim as new and desire to secure by Letters Patent is:

1. An envelope opener comprising a holder in the form of a plate folded upon itself to constitute a thin flat sheath, and a 25 blade pivoted adjacent one end thereof to said holder, said blade having a relatively

wide inner portion to constitute a finger-piece and tapering thence to a relatively narrow outer portion engaged frictionally within said sheath when closed, a corner of 30 said blade engaging said holder to limit the opening of the blade to a predetermined angle with respect to the holder.

2. An envelope opener comprising a holder in the form of a plate folded upon 35 itself to constitute a thin flat sheath, a blade pivoted adjacent one end thereof to said holder, said blade having a relatively wide inner portion to constitute a finger-piece and tapering thence to a relatively narrow 40 outer portion engaged frictionally within said sheath when closed, a corner of said blade engaging said holder to limit the opening of the blade to a predetermined angle with respect to the holder, and a member extending laterally from said sheath to constitute a hand-piece.

In testimony whereof, I have hereunto 45 subscribed my name this 22nd day of July, 1921.

WILLIAM L. BARBER.
